AUTOMATIC TIMER FOR TOASTERS OR
OTHER APPARATUS

Lester E. Padelford, North Arlington, N. J., assignor to The Olijak Manufacturing Co., Inc., Montclair, N. J., a corporation of New Jersey

Application November 22, 1946, Serial No. 711,544

5 Claims. (Cl. 161—1)

1

The invention here disclosed relates to timing mechanism and particularly for apparatus such as toasters, involving heat or other variables.

As a practical application the invention relates to toasters of the type disclosed in the Warner Patent No. 2,371,084 of March 6, 1945, in which the toasting time is divided up into two periods, a first or initial period of predetermined duration and a second period of variable duration, dependent upon heat conditions in the apparatus at the time.

Particular objects of the invention are to provide a timer of simple, inexpensive and practical construction which will operate on the principle outlined, with a predetermined first period and a variable second or final period.

Further objects are to provide such mechanism in a form which can be readily combined with clock escapement mechanisms of more or less conventional or accepted design.

Other desirable objects and the novel features through which the purposes of the invention are attained are set forth or will appear in the course of the following specification.

The drawing accompanying and forming part of the specification illustrates a present commercial embodiment of the invention. Structure, however, may be modified and changed as regards the immediate illustration, all within the true intent and broad scope of the invention as hereinafter defined and claimed.

Fig. 1 in the drawing is a broken part sectional view of a clock movement having the invention incorporated therein, this view being taken as with the front plate of movement removed and showing the parts in the idle position.

Fig. 2 is a similar and more fragmentary view showing the trip lever lowered to start the timing train;

Fig. 3 is a detached view of the variably set cam lever for determining the duration of the second heat period above referred to.

In the illustration, portions of a standard time train are shown made up of a trip lever 5 pivoted on a center 6, tensioned by a spring 7 and carrying a spring pawl or dog 8 engageable with the tooth 9 of a cam segment 10 coupled through a spring clutch 11 with a main gear 12 in driving engagement with the escapement train indicated generally at 13.

In this particular embodiment, downward movement of lever 5, which may be effected by the lowering of the bread slide of the toaster, from the Fig. 1 to the Fig. 2 position, tensions the spring 7 and thus sets the escapement mechanism into

2

operation. Upward movement of this lever continues until the dog 8 is released from the tooth 9 of segment 10 whereupon the lever snaps upward, in the case of the ordinary toaster, to trip the latch holding the toaster in operation.

The present invention involves the provision of a special cam lever for tripping the dog 8, which in the example is set according to existing temperature conditions, and variable coupling means 10 which after a predetermined initial period of operation will automatically lock said cam lever in the position in which it has been set, to trip the dog at the end of the second, variable period, determined by such setting and locking of the trip cam.

The variable timing cam is shown in the form of an arcuate or segmental lever 14, pivoted on the center 6, having a short cam track 15 engageable by the roll 16 on the dog 8 and provided with 20 a toothed segment 17 engageable by a holding tooth 18 on a locking lever 19.

The lever 19 is shown pivoted at one end at 20 so as to swing to carry the holding tooth 18 into engagement with the toothed segment 17 and tensioned toward such segment by a spring 21.

A special feature of the locking lever 19 is that on the edge toward the segment it is formed with two cam tracks 22, 23, one in extension of the other and engageable successively by a roller 24 30 on the trip lever.

These two cam tracks may be considered as representing the two toasting intervals, the lower cam surface 22 representing the first predetermined interval and the upper track 23 representing or providing for the second variable time interval.

The lower, fixed-period cam track 22 may be substantially concentric with the arc of travel of the roller 24, since for this period it is only 40 essential that the locking tooth 18 be held out of engagement with the segment 17. This track terminates in a definite high point 25 from which the upper track 23 fades outwardly relatively rapidly so as to let the holding tooth on this lever come inwardly into engagement with the segment of the timing cam as soon after the end of the first period, as may be determined by the timing cam.

During the preliminary fixed interval and for 50 as long thereafter as determined by the design of the second cam 23, the timing cam 14 is free, as shown in Fig. 2, and may be freely shifted, for example, by a thermostat, by air pressure, by a magnet, by hand, or otherwise. In the example 55 the end of a thermostatic bar or thermostatically

actuated lever is represented at 26 in Fig. 1, engaged with a finger 27 on the upper end of the cam lever 14. As a consequence this lever, while free as in Fig. 2, will be positioned by the bimetal or like element, and this positioning locates the cam 15 in position to be engaged by the roller 16 and release the dog 8 at a certain time in the upward spring impelled travel of the trip lever 5, thus to effect the uncoupling of this lever from the time train segment 10 an elapsed time after the end of the first predetermined interval.

The operation will be clear from the foregoing. The lever 5 which is to release the latch holding the toaster in operation, or perform some other useful function, is spring tensioned by forcing it downward from the Fig. 1 to the Fig. 2 position. In such motion the shoulder 28 at the heel of the dog 8, encounters the back of the segment 10 to carry the same forwardly, this being permitted through the slip of the spring clutch 11 without disturbing the escapement train. At the end of the downward movement of lever 5, with the dog 8 dropped in engagement with the tooth 9, the lever will be coupled to the escapement and hence the power of the spring 7, tensioned by the lever, be applied to the escapement train.

In this downward movement of lever 5 for tensioning the drive spring and coupling the lever to the escapement, the roller 24 on the lever encounters first the non-concentric cam surface 23 to start the spring loaded cam lever 19 swinging outwardly to clear the holding tooth 18 from segment 17, and then the more or less concentric cam 22 to hold the cam lever in such relation freed from the segment of the timing lever 14. The latter, now freed of the locking lever 19, is shiftable by thermostatic or other means and therefore assumes a position as determined by such means. This position may vary in the time interval that the roller 24 is traveling over the fixed-interval cam 22 and beyond that on over the variable time-interval cam 23, so that the device is sensitive to varying temperature changes. The roller 24, as it rides up the cam 23, allows the locking lever 19 to swing inwardly until a point is reached where the locking tooth 18 engages a tooth in the segment 17 and thereupon secures the timing cam in the position to which it has been shifted by the thermostat. The dog 8 will then be tripped by engagement of the roll 16 with the cam 15, in accordance with that particular setting and securing of this timer cam. On such release of the dog the spring tensioned trip lever 5 is uncoupled from the drive segment 10 at the head of the escapement train and hence is freed to be snapped upwardly by spring 7 into the position shown in Fig. 1.

In the released idle position of the parts shown in Fig. 1, the locking lever 19 holds the timing cam 14 in the position to which it was last set, but the bimetal of the thermostat ordinarily is sufficiently flexible to accommodate itself to this condition without injury to any of the parts and when unlocked as in Fig. 2, the bimetal may then assert itself to set the timing cam in proper position for the then existent temperature conditions.

The parts required to make up the invention are relatively few, of inexpensive construction and can be readily combined with escapement mechanisms of approved design. While of particular importance for use with toasters, broilers and the like, it will be apparent that the invention may have many other uses and that the setting of the second variable time interval may

be either automatic, as described, or the device be set manually or otherwise.

What is claimed is:

- 5 1. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 10 2. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 15 3. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 20 4. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 25 5. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 30 6. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 35 7. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 40 8. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 45 9. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 50 10. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 55 11. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 60 12. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 65 13. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 70 14. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.
- 75 15. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever.

interval afforded by engagement of the roller with the first and second cam sections.

4. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion toothed detent elements on said locking lever and timing cam engageable in different relations in the different positions of said timing cam, said locking lever and said spring tensioned lever having companion cam and roller elements engageable in the movement of said spring tensioned lever to effect release of said companion detent elements in one range of travel of said spring tensioned lever and to permit engagement of said companion detent elements in another range of travel of said spring tensioned lever, said detent elements including a toothed segment on said timing cam and a tooth on the locking lever engageable therewith and said companion cam and

roller elements including a roller on said spring tensioned lever and a cam face on said locking lever.

5. A timer comprising an escapement, a spring tensioned lever for powering said escapement, means for coupling said lever to said escapement, a timing cam for effecting uncoupling of said lever from the escapement, said timing cam being shiftable into different positions of timing adjustment, a spring tensioned locking lever, companion coupling elements on said locking lever and timing cam engageable in different relations in the different positions of said timing cam, said locking lever and said spring tensioned lever having companion cam and roller elements engageable in the movement of said spring tensioned lever to effect release of said companion coupling elements in one range of travel of said spring tensioned lever and to permit engagement of said companion coupling elements in another range of travel of said spring tensioned lever.
